UNITED STATES PATENT OFFICE

RICHARD C. COOK, OF AURORA, ILLINOIS, ASSIGNOR TO GIFFORD-WOOD COMPANY, OF
HUDSON, NEW YORK, A CORPORATION OF NEW YORK

BUCKET GUIDING ATTACHMENT FOR TRAVERSING HOISTS

Application filed October 12, 1928. Serial No. 312,150.

This invention relates to traversing hoists of the type employing flexibly suspended dump buckets such as are used for handling coal or other more or less fluent materials and aims to provide an improved bucket guiding attachment for the trolley adapted to prevent swinging or twisting movements of the bucket when it approaches the upper limit of its travel.

10 This application involves an improvement in the device shown in the co-pending application of Willis H. Towne, Serial No. 146,890, filed November 8, 1926.

In the accompanying drawings wherein 15 one illustrative embodiment of the invention is shown,

Fig. 1 is an elevation, partly in section, showing a traversing hoist installation for handling coal and the like, having the improved bucket guiding attachment associated therewith;

Fig. 2 is an end elevation, on an enlarged scale, of the trolley shown in Fig. 1; and

Fig. 3 is a side elevation of the trolley on 25 a somewhat smaller scale than Fig. 2.

As explained in the aforesaid Towne application, flexibly suspended traversing hoist buckets are subject to swinging and twisting movements which might result in considerable damage, and usually cause a loss of time. Such movements take place when the bucket is being hoisted and when the trolley is started or stopped or its speed is changed. This invention aims to provide an improved buck-

35 et guide associated with the trolley arranged to overcome such movements when the bucket approaches the upper limit of its hoisting movement and to guide the bucket to its proper position with respect to the trolley.

40 Referring to Fig. 1, the preferred form of the guiding attachment is shown as applied to a traversing hoist wherein a monorail trolley 10 is employed. From the trolley is flexibly suspended a dump bucket 11, which 45 is provided with rollers 12 adapted to be guided on an inclined track 13 into a pit where the bucket is adapted to be filled by means of a gate 14 on a receiving bin 15, the pit installation being substantially the 50 same as that shown and described in the pat-

ent issued June 9, 1931, to Gifford-Wood Company, No. 1,808,972. The bin 15 is adapted to be filled by a railroad car 16 or the like. The operation of the installation is adapted to be controlled by suitable control mechanism located in a power house 17, the arrangement being such that the bucket is lowered into the pit; then elevated on the inclined tracks 13 to a position below the trolley; and then hoisted vertically so that it can be carried by the trolley over any one of a series of storage bins 18 where the material is to be stored.

Referring now to the trolley and bucket installation, the bucket 11 is suspended in the bight of a cable 19, trained over a pair of sheaves or pulleys 20 on the trolley and around a hoisting block 21 on the bail 22 of the bucket, the bail being preferably carried normally in the plane of the two sheaves 20, the arrangement being such that a single cable may be hauled in to hoist the bucket above the series of bins 18 over which the trolley travels. The preferred construction of the bucket is described in Patent No. 1,741,123 of A. C. Bennett, being adapted to be dumped automatically upon striking against the material in one of the bins.

Herein, the trolley 10 is shown as having a pair of spaced buffer plates 23 arranged at the opposite ends thereof, each of the buffers having compression springs 24 conveniently like those shown in the aforesaid Towne application.

To afford ample guiding surfaces to co-operate with the bucket when it is being hoisted, a substantially V-shaped frame 25 is suitably secured to the side of each buffer plate 23. Herein, each frame comprises a plate 26 having a substantially V-shaped notch riveted to structural members 27 on the plate and is arranged on the inside thereof as shown in Fig. 3. At the edges of the V-shaped notch there are shown a pair of structural angles 28, each having one flange riveted or otherwise secured to the plate to present a relatively wide and rigid bearing surface for the bucket bail 22. As shown in Figs. 1 and 2, the lower ends of the angle members preferably extend below the lower

ends of the plates 26 and are bent or curved outwardly so that when the bucket is being hoisted and has a relatively wide pendulum-like swinging movement, the bail may engage 5 either of the curved ends of hooks and be guided thereby.

From the foregoing description, it will be seen that the opposite ends of the cross member of the bail 22 will be guided by the spaced 10 guiding members and will cause the bail to strike the buffer plates substantially centrally thereof or in the plane of the sheaves, so that the bucket cannot swing in the plane 15 of its traversing movement or the traversing movement of the trolley. This is very important because, if the bail should lie in a plane at a substantial angle to the longitudinal center line of the trolley, the bucket would swing when the trolley started or 20 stopped or its speed is changed. Moreover, the V-shaped guides will quickly stop any twisting movements of the bucket during the 25 final stages of the hoisting movement. This is of importance because the twisting and swinging movements would otherwise cause a loss of time while the operator endeavored to straighten the bucket with respect to the trolley.

In view of the explanation of the advantages of a bucket guide and stabilizer described in the aforesaid Towne application, it is not believed to be necessary further to elaborate on them in this application.

Obviously, the present invention is not restricted to the particular embodiment thereof herein shown and described.

What is claimed is:—

1. In combination with a traversing hoist trolley and a bucket flexibly supported from the trolley, a pair of sheaves on the opposite ends of the traversing hoist trolley; a cable over said sheaves presenting a bight portion suspending said bucket; a bail on the bucket; and spaced, V-shaped guiding frames on the trolley below the sheaves for co-operation with said bail and constructed and arranged to guide it in substantially the same plane as the spaced sheaves and bring the bucket to rest with respect to the trolley.
2. In combination with a monorail traversing hoist having a bucket flexibly suspended from a hoist line, and a trolley supporting the hoist line; said bucket having a bail; a pair of spaced guiding members, each of which has two upwardly converging guiding surfaces, secured to and extending below the trolley and constructed and arranged to receive the bail of the bucket, and contact therewith at spaced points, when the bucket is at and near its uppermost position, to check oscillations of the bucket in a plane perpendicular to the vertical plane of the monorail and to check oscillations about a vertical axis passing through the bucket.
3. In combination with a traversing hoist

having a trolley carrying a suspended dump bucket, a bail on the bucket; spaced buffers carried by the opposite ends of the hoist trolley; and depending substantially V-shaped guide members carried by said buffers and 70 cooperating with said bail.

4. In combination with a traversing hoist, carrying a suspended dump bucket, a bail on the dump bucket; a hoisting block carried by the bail; a pair of sheaves on the hoist trolley over which the bucket suspension cable is carried; buffer plates mounted on the opposite ends of the hoist trolley; and depending, substantially inverted V-shaped bail guiding members associated with said 75 buffer plates and having outwardly curved lower ends to engage the bucket bail initially to check pendulum swinging movement of the bucket and guide it so that the bail finally lies in a vertical plane extending 80 along the direction of travel of the trolley.

5. In combination with a traversing hoist having a flexibly suspended bucket, a pair of buffer plates associated with the hoist trolley; sheet metal plates secured to the buffer plates and depending therefrom, said plates having V-shaped notches therein; and structural angle members secured to said plates at the edges of said V-shaped notches, said structural angle members being bent 85 outwardly at their lower ends and extending below the ends of said plates to present initial guiding surfaces for the bucket during the latter part of its hoisting movement.

In testimony, that I claim the foregoing 100 as my own, I have hereto affixed my signature.

RICHARD C. COOK.
